UNITED STATES PATENT OFFICE

SYLVANUS D. LOCKE, OF BRIDGEPORT, CONNECTICUT

ASH TRAY AND RECEIVER

Application filed December 24, 1927. Serial No. 242,374.

This invention relates to a novel ash tray and receiver, and the general object of the invention is to provide an ash tray and receiver detachably associated with each other in such manner that the tray can be rotatable upon the receiver to be capable of swinging between a closed, smoke-tight position and a wide open position, but can be removed from said receiver only when in open position.

10 A more specific object is to provide an ash tray and receiver having complementary means upon the tray and receiver for rotatably and detachably mounting said tray on said receiver so that the tray can be swung upon the receiver between a closed and an open position, and said mounting means for said tray will be adapted to preclude removal of the tray from the receiver when in closed position upon said receiver.

15 A further specific object is to provide an ash tray and receiver more especially adapted for use in automotive vehicles, which ash tray and receiver will include complementary means for rotatably and detachably mounting said tray on said receiver so that the tray can be swung upon the receiver between a normally closed position and an open position, and said mounting means for said tray will be adapted to preclude removal of the tray from the receiver except when the tray is intentionally moved to open position, whereby to preclude the accidental removal of said tray from said receiver (as, for example, by reason of shocks imparted to the automotive vehicle) when in its normally closed position.

20 And a still further specific object of the invention is to provide in the device an arrangement for mounting the rotatable and detachable tray in the receiver in such manner that when said tray is swung to wide open position there will be provided between the upper face of the tray body and the receiver mouth an opening greater than one-half of the area of said mouth of the receiver.

25 With the above objects in view, as well as others which will appear as the specification proceeds, the invention comprises the construction, arrangement and combination of parts as now to be fully described and as hereinafter to be specifically claimed, it being un-

derstood that the disclosure herein is merely illustrative of the principles of the invention and meant in no way in a limiting sense, changes in details of construction and arrangement of parts being permissible so long as within the scope of the appended claims.

55 In the accompanying drawing forming a part of the specification—

Fig. 1 is a front elevational view of an ash tray and receiver in which the features of the invention are incorporated, disclosing the tray in closed position;

Fig. 2 is a side or end elevation, showing the tray closed;

Fig. 3 is an enlarged fragmentary sectional view, taken as on line 3—3 in Fig. 1, disclosing, in dotted lines, the tray in closed position and in full lines, the tray as when rotated to open position and removed from the receiver;

Fig. 4 is a fragmentary sectional view, taken as on line 4—4 in Fig. 3, detailing the complementary means for mounting the tray in the receiver; and

Fig. 5 is an enlarged fragmentary sectional view, agreeing with the disclosure of Fig. 3, but disclosing a modified form of complementary means for mounting the tray in the receiver, said tray being illustrated, in full lines, in closed position, and in dotted lines, so in open position and partially removed from the receiver.

70 With respect to the drawing and the numerals of reference indicated thereon, 10 denotes the receiver and 11 represents the tray of the novel device of the invention.

The receiver 10 as disclosed consists of a base 12, parallel front and rear walls 13, parallel side or end walls 14, said walls 13 and 14 being perpendicular to the base 12, and an open mouth 15 about which a skirt 16 is preferably situated, or the receiver can be of any other convenient box-like construction.

The ash tray 11 and its manner of association with the receiver is best disclosed in Figs. 3 and 4. In said figures, the tray is disclosed as of general curvilinear shape to fit within the mouth 15 of the receiver. It includes a body having a smoothly curved portion 17 adapted to lie within the upper, open

70

end or mouth 15 of the receiver contiguous with the front and rear walls 13 when the tray is in closed position; side or end walls 18 upon said smoothly curved portion 17 adapted to lie within said mouth contiguous with or adjacent to the side or end walls 14 of the receiver; and a finger piece 19 upon said smoothly curved portion adapted to be positioned at the rear of and above the receiver when the tray is closed. See Figs. 1, 2 and 4 and the dotted line tray in Fig. 3.

As disclosed, each side or end wall 14 has an inwardly extending pin or axis 20 supported upon the receiver in any suitable way, as, for example, by riveting to said receiver, said pins or axes of the different side or end walls 14 being arranged opposite each other. In the instance of Figs. 1 to 4, the pins or axes are arranged closer to the front wall than to the rear wall of the receiver. In the case of Fig. 5, the pins or axes are adjacent the rear wall.

The side or end walls 18 of the tray of Figs. 1 to 4 extend upwardly from said tray when closed, while the side or end walls 18' of the tray of Fig. 5 extend downwardly. In the instance of all of the figures, the side or end walls 18 or 18', as the case may be, have sockets or slots, represented 21 and 21', respectively, extending to edges of said side or end walls, adapted to receive the pins or axes 20.

As will be very clear from Fig. 3, the sockets or slots 21 are situated to extend horizontally, or at right angles to the front and rear walls of the receiver, when the tray is in closed position, numeral 22 representing enlarged mouths of said sockets or slots.

As will be clear from Fig. 5, the sockets or slots 21' are situated to extend obliquely of the front and rear walls when the tray is in closed position.

To assemble the tray of either form of the invention with the receiver, said tray is first positioned above the receiver so that the sockets or slots 21 or 21', as the case may be, open downwardly about in parallel relation to the side walls of the receiver and are in alignment with the pins or axes 20, as the full line tray is illustrated in Fig. 3. The tray is then lowered vertically (see, the dotted tray in Fig. 5) until the bases of the sockets or slots rest upon the pins or axes 20. The tray is now assembled, but in its wide open position. To close the tray, the finger piece is next swung downwardly, from left toward right as in Figs. 2, 3 and 5, to move the tray about the pins or axes 20 as pivots. The arrangement is such that when said finger piece is so swung downwardly for a sufficient distance, the forward edge 23 of the tray engages the inner face of the forward wall of the receiver at a location somewhat beneath the mouth of the receiver and the rearward face of the rearward part 24 of the smoothly curved portion

17 comes into contact with the inner face of the rearward wall of the receiver adjacent its upper, open end. See the dotted line tray of Fig. 3 and the full line tray of Fig. 5. To remove the tray from the receiver, the operations as described are reversed.

It will be evident that neither the tray of Figs. 1 to 4 nor the tray of Fig. 5 when in closed position can be removed from the receiver until first swung to open position, so that the tray when closed is not liable to become accidentally displaced from the receiver by shocks imparted to an automotive vehicle having the tray and receiver. At the same time, the tray can be very easily removed from the receiver, when this is the intention, by first rotating said tray upon the complementary pivotal means of the tray and receiver to the open position of the tray.

The tray of Figs. 1 to 4 is not liable to become accidentally rotated to open position and thrown from the receiver by a bounding automotive vehicle for the reason that when said tray of Figs. 1 to 4 is closed, the bulk of the weight of the tray is at the side of the tray axes tending to insure that the closed position of the tray is its normal position. To make more certain that the tray of either form of the invention when in closed position will not become accidentally displaced, the finger piece 19 can be weighted, as will be apparent. Or the fit of the lower face of the rearward part of the smoothly curved portion 17 of the tray against the rearward wall of the receiver at the location of the receiver mouth can be a tight fit. The fit will be a resilient one when either the tray or the receiver is composed of resilient material.

In the instance of both forms of the invention, it will be obvious that when the tray is swung to wide open position there will be provided between the upper face of the tray body and the receiver mouth an opening greater than one-half of the area of said mouth of the receiver.

Attention is called to the fact that the ash containing portion of the tray does not become removed from the receiver during its normal use, and therefore, the tray of Fig. 5 needs no upstanding side or end walls.

What I claim is:

1. In combination, an ash receiver having an upper open end, and an ash tray adapted to rotatably fit in said upper open end of the receiver, said tray and receiver having cooperating pivotal means for the tray, arranged at the opposite sides of the tray and receiver, adapted to permit rotation of said tray upon said receiver between a closed position and an open position, and said cooperating pivotal means adapted to permit removal of the tray from the receiver only when the tray is in open position.

2. In combination, an ash receiver having an upper, open end, and an ash tray adapt-

ed to fit in said upper, open end of the receiver and having end walls lying next to the receiver walls adjacent the open end of the receiver, said ash tray being adapted to cover said upper, open end of the receiver in smoke-tight fashion, and cooperating pivotal means for said tray, arranged in the end walls of the tray and in opposite sides of the receiver, said co-operating pivotal means adapted to permit swinging movement of said tray upon said receiver between a closed and an open position, and said co-operating pivotal means adapted to permit removal of said tray from said receiver when the tray is in open position but to preclude removal of the tray from the receiver so long as said tray is in closed position upon the receiver.

3. In combination, an ash receiver having an upper, open end, an ash tray having a smoothly curved portion adapted to fit in said upper, open end of the receiver and end walls extending at right-angles to said smoothly curved portion lying next to and in contact with and parallel to the receiver walls within the receiver adjacent the open end thereof, complementary means upon said end walls of the tray and said parallel receiver walls adapted to permit rotation of said tray upon the receiver between a closed position and an open position and adapted to permit removal of said tray from the receiver only when the tray is in open position, and a finger piece upon said tray and extending outwardly beyond the upper, open end of the receiver.

4. In combination, an ash receiver having an opening, an ash tray closing said opening, a pin and slot connection between said tray and receiver whereby the tray is pivotally movable between open and closed positions relative to the receiver, the slot of said pin and slot connection extending at an angle other than ninety degrees to the surface of said opening when the tray is in receiver closing position whereby to prevent casual displacement of the tray.

5. In combination, an ash receiver having an open end, an ash tray normally closing said open end, a pin and slot connection between said tray and receiver, and said pin and slot so disposed as to prevent removal of the tray from the receiver while the tray is in receiver closing position.

6. In combination, an ash receiver having an open end, an ash tray normally closing said open end, means pivotally and removably mounting said tray on said receiver, said means preventing removal of the tray from the receiver while the tray is in receiver closing position.

7. In combination, an ash receiver having an elongated mouth opening, an ash tray disposed in said mouth opening, flanges on the ends of said tray, each of said flanges having a slot, pins extending inwardly from the end walls of said receiver, said pins en-

tering said slots and pivotally mounting the tray for movement between an open and a closed position.

8. In combination, an ash receiver having an open upper end, an ash tray disposed in said open end, flanges on said tray within said receiver, said flanges having openings, pins extending inwardly from the walls of said receiver, said pins entering said openings in the flanges and pivotally mounting the tray.

9. The combination as in claim 4 wherein the slot is disposed at an angle of ninety degrees to the opening when the tray is in open position whereby to permit withdrawal of the tray from the receiver when the tray is in open position.

10. A device as in claim 5 wherein the pin and slot connection is so arranged as to permit withdrawal of the tray from the receiver when the tray is in open position.

Signed at Bridgeport, in the county of Fairfield, and State of Connecticut, this 30th day of November, A. D., 1927.
